[57] CLAIM

The ornamental design for a bottle, as shown and described.

DESCRIPTION

FIG. 1 is a perspective view of a bottle, showing the top,

right side and front of an embodiment of our new design in which dispensing port covers are provided on both right and left halves of the bottom;

FIG. 2 is a front view of an embodiment of the bottle of FIG. 1;

FIG. 3 is a back view of the bottle of FIG. 1;

FIG. 4 is a right side view of the bottle of FIG. 1;

FIG. 5 is a top view of the bottle of FIG. 1;

FIG. 6 is a bottom view of the bottle of FIG. 1;

FIG. 7 is a perspective view of a bottle, showing the top, left side and front of an embodiment of our new design in which a dispensing port cover is provided only on the right half of the bottom;

FIG. 8 is a front view of the bottle of FIG. 7 or, if the lower half of the figure is rotated 180°, of a bottle having a dispensing port cover only on the left half of the bottom;

FIG. 9 is a back view of the bottle of FIG. 7 or, if the lower half is rotated 180°, of a bottle having a dispensing port cover only on the left half of the bottom;

FIG. 10 is a view of the left side of the bottle of FIG. 7 or, if the lower half is rotated 180°, the right side of a bottle having a dispensing port cover only on the left half of the bottom;

FIG. 11 is a view of the right side of the bottle of FIG. 7 or, if the lower half is rotated 180°, of the left side of a bottle having a dispensing port on the left half of the bottom;

FIG. 12 is a top view of the bottle of FIG. 7; and,

FIG. 13 is a bottom view of the bottle of FIG. 7 or, if rotated 180°, of a bottle having a dispensing port cover only on the left half of the bottom.
